UNITED STATES PATENT OFFICE.

CHARLES C. BURDINE, OF WASHINGTON, DISTRICT OF COLUMBIA, ASSIGNOR TO
MERGENTHALER LINOTYPE COMPANY, A CORPORATION OF NEW YORK.

TYPE OR MATRIX.

1,099,485.

Specification of Letters Patent.

Patented June 9, 1914.

Application filed December 10, 1912. Serial No. 735,911.

To all whom it may concern:

Be it known that I, CHARLES C. BURDINE, a citizen of the United States, and a resident of Washington, District of Columbia, have 5 invented a new and useful Improvement in Type or Matrices, of which the following is a specification.

My invention relates to typographical machines, such as linotype machines of the general organization represented in Letters Patent of the United States to O. Mergenthaler, No. 436,532, wherein circulating matrices are released from a magazine in the order in which their characters are to appear in 10 print and then assembled in line, the composed line transferred to the face of a slotted mold, the mold filled with molten metal to form a slug or linotype against the matrices which produce the type characters thereon, 15 and the matrices thereafter returned through a distributing mechanism to the magazine from which they started.

More particularly, it relates to a special form of circulating matrix for use therein, 20 the construction being such that one or another of a plurality of characters thereon may be brought into operative position at will.

Referring to the drawing, I have shown 25 my invention in preferred form and by way of example, and as applied to the kind of matrix shown and described in the said Mergenthaler patent, or as employed in the commercial linotype machine, but obviously many changes and variations therein, and 30 in its mode of application, will suggest themselves to those skilled in the art, without departure from its scope. Thus, it may be used in connection with other styles of typographical machines, or with typecasters, 35 typesetters, or the like, or any machines which handle type or dies instead of matrices. Generally speaking, I desire it to be understood distinctly that I do not limit myself to 40 the specific forms or embodiments herein 45 illustrated and described.

Referring to the drawing: Figure 1 is a side view of a matrix with my invention applied thereto; Fig. 2 is a similar view, showing the parts in different relation; Fig. 3 50 illustrates a modification; Figs. 4 and 5 are sectional views, taken respectively on the lines 4-4 and 5-5 in Fig. 2; Fig. 6 is a 55 perspective view of the matrix body; Figs. 7, 8 and 9 are detached views of different

forms of the character-bearing member; and Figs. 10 and 11 show a modification in perspective and edge view respectively.

The matrix comprises the body portion A, formed with the distributing combination 60 A¹, which latter is designed to coöperate with the well known distributor rail or bar. The body A is recessed as at A² (see Fig. 6) to receive the annular character-bearing member B (see Fig. 7), which is held in close 65 relation thereto, as by being pivotally connected thereto at C, as shown in Figs. 1, 2, 4 and 5. The member B is formed with a plurality of matrix characters B¹, B¹, any one of which may be brought into operative 70 position by the rotation of the member about its pivot. In Fig. 1 the upper matrix character is thus shown, and in Fig. 2 the lower matrix character. The member B is also provided with stop shoulders B³, B³, which 75 engage respectively with the limiting edges A³, A³, of the body A, in order to position and set the selected character in proper relation to the body, namely, with the matrix character B¹ in the front edge of the matrix, 80 it being then normally held therein by the close frictional engagement of the parts.

Figs. 3, 8 and 9 show a modification, 85 wherein the character-bearing member D is in the form of a polygon, preferably a hexagon. By this arrangement, when the character D¹ is in operative position, namely, in the front edge of the matrix, the opposite parallel edge is located in the rear edge of the matrix. This construction of 90 the parts insures the proper coöperation of the matrix with the mold and the other related elements of the machine. In Fig. 3, the matrix character-bearing member D is 95 shown as provided with a square recess C¹, which may be engaged by a transverse key or shaft, so as to shift the member, or a plurality thereof simultaneously, from one operative position to another at will.

The characters may be arranged in any 100 desired manner or sequence on their supporting members. For instance, in Figs. 7 and 8, the upper and lower halves of a two-line character are illustrated, while Fig. 9 shows the upper character in Roman upper 105 case and the lower character in italic upper case.

In Figs. 10 and 11, I show still another 110 modification, wherein the matrix body E is formed of thin sheet metal, such as steel,

and is offset to form the ears E¹ and also to give it sufficient thickness to receive the character-bearing member F, pivotally connected thereto at G.

5. It will be noted that in all of the forms shown, the character-bearing members are detachably connected to the bodies, so that they may be removed and others substituted therefor at will. This feature is of importance, in that it permits the employment of matrix bodies in stock, and their provision with any characters desired, and also allows the characters to be replaced when worn. It will also be seen that by the use 10 of my improved matrix, I am enabled to dispense with the mechanism ordinarily employed in connection with plural letter matrices, this being due to the fact that the characters themselves are severally and independently adjustable and usable.

It will be obvious that means may be provided for the mechanical adjustment of the character-bearing members, although such means constitute no part of my present invention, which relates solely to the construction of the matrix itself. Or if desired the adjustment of the character-bearing members may be effected by hand, either before 25 the matrices are put into the magazine or after they have been set in line, according to the uses to which they are put.

Having thus described my invention, its construction and mode of operation, what I claim and desire to secure by Letters Patent 30 of the United States is as follows:

1. A type or matrix adapted for circulation in a typographical composing machine and having relatively movable plural letter characters, any one of which may be brought into operative position thereon, as desired.
2. A type or matrix adapted for circula-

tion in a typographical composing machine and provided with a relatively movable character-bearing member which may be set in different positions thereon.

3. A type or matrix adapted for circulation in a typographical composing machine and provided with a relatively rotatable character-bearing member.

4. A type or matrix adapted for circulation in a typographical composing machine and provided with an adjustable character-bearing member frictionally engaging therewith so as to be maintained in its adjusted positions thereon.

5. A type or matrix adapted for use in a typographical machine comprising a body portion and a rocking character-bearing member secured thereto.

6. A type or matrix adapted for use in a typographical composing machine comprising a body portion, a rocking character-bearing member, and a pivot passing through said parts and securing them together.

7. A matrix adapted for circulation in a typographical composing machine and provided with a movable character-bearing member arranged so that its characters may be moved into the plane of the matrix edge.

8. A matrix adapted for circulation in a typographical composing machine and provided with a rotatable polygonal character-bearing member arranged so that its opposite edges will lie in the planes of the matrix edges.

In testimony whereof I hereunto set my hand this 7th day of December, 1912, in the presence of two attesting witnesses.

CHARLES C. BURDINE.
